UNITED STATES PATENT OFFICE.

JOSE GONZALEZ BABIO, OF NEW YORK, N. Y.

WINDOW-CLEANING CHAIR.

947,191.

Specification of Letters Patent. Patented Jan. 18, 1910.

Application filed October 19, 1908. Serial No. 458,511.

To all whom it may concern:

Be it known that I, JOSE GONZALEZ BABIO, a citizen of the United States, residing at New York city, borough of Manhattan, and 5 county and State of New York, have invented certain Improvements in Window-Cleaning Chairs, of which the following is a specification.

The invention relates to that class of 10 chairs known as window cleaning chairs, and the purpose of the invention is to provide a chair of this type that will be simple, as light as possible, consistent with strength, and which in addition to being economic in 15 manufacture, will be absolutely safe and convenient to the operator under all conditions of use.

It is a further purpose of the invention to 20 provide a chair of the character described that can be readily adapted to any window sill or frame, and in which a person can be safely seated, occupying such position that windows can be cleaned inside or out, the top sash being as readily accessible as the 25 bottom one.

It is also a purpose of the invention to so 30 construct the chair, that the occupant will be concealed from the public, and to provide a construction whereby the chair may be rendered exceedingly compact when not required for use.

In the drawings that serve to illustrate 35 my invention, I have shown the preferred form of the chair, but I desire it to be understood that the details of construction may be varied without departing from the spirit of the invention.

In the drawings—Figure 1 is a rear elevation of the chair applied to a window 40 frame; Fig. 2 is a section through the window frame, and a plan view of the chair with the seat removed; Fig. 3 is a detail vertical section through the chair, the section being taken on the line 3, 3, of Fig. 1; Figs. 45 4 and 5 are detail views of different means for locking the chair in place, and Fig. 6 is a transverse section of an adjustable leg support for the chair.

As has been stated, the chair is adapted 50 to any type of window frame A, and in connection with a window frame, I employ stationary fixtures of a simple construction whereby to readily and expeditiously attach the improved chair and remove it from locking engagement with the window frame or 55 sill A'.

In Figs. 4 and 5, I have shown two forms of such devices designated, respectively as *a* and *b*. The device *a*, shown in Fig. 4, is in the nature of a hook having a screw shank 60 10, and a flange 11, at the junction of the hook body with the shank. This flange may be apertured to receive wood screws and the shank may be in the form of a spike, and when the shank is threaded, the screw holes 65 may be omitted from the said flange. Any desired number of said retaining fixtures may be employed and are properly distributed at the inner face of the window sill A', as is shown in Figs. 2 and 3. The hook-like 70 devices *a* are adapted to be secured upon the inner surface of the window casing below the window sill, as clearly shown in Fig. 3.

With reference to the fixture *b*, illustrated in Fig. 5, it is in the form of a socket 75 plate, having a curved diagonal or circuitous slot 12, produced therein. Suitable members are provided for the seat frame B, of the chair, as will be hereinafter described, fitted to the fixture, shown in Fig. 4, or that shown 80 in Fig. 5. As herein shown, the frame B of the seat is of skeleton construction, and may be made in one piece, or a series of pieces may be employed in constructing the frame, and the members of the frame may be of 85 angle iron shape in cross section, or may partake of a T, or a channel iron construction. As illustrated, the angle iron formation is employed and the frame B consists of a rear section 13, that is secured in any 90 suitable or approved manner to the sides of a body section 14, having bracing ribs 15, and a front bar 16, either removable from or integral with the sides of the body portion of the frame.

The seat proper 17, which may be a board 95 or its equivalent rests upon the back section 13, of the frame and the forward cross bar 16, as is shown in Fig. 3, but other means may be employed for its support, and any 100 desired number of transverse brace bars may be employed in the construction of the seat frame, as is illustrated at 18, in Fig. 2. As herein shown the forward end portions of the seat frame B, and also when desired its 105 forward central portion, downwardly extending latch members 19, are provided which may be either integral with or attached to said frame and each latch member 19, is provided with an eye 20, that receives 110 a hook body of the type of fastening devices *a*, shown in Fig. 4, which devices are

practically keepers. The hook-like members *a* have downwardly directed bills which are adapted for locking engagement with the eyes 20, when the seat portion is supported upon the window sill, as shown in Fig. 3. When, however, the form of fastening device *b* is employed, shown in Fig. 5, downwardly extending members 19^a are used instead of the members 19, and the said members 19^a, instead of terminating in eyes 20, terminate in curved or angular tongues 20^a, that enter the slots 12, in the said keepers or fastening devices *b*. In this manner the forward portion of the chair may be quickly and securely attached to the inner portion of any window sill.

With reference to the means of support for the outer or back portion of the chair, said supporting means is capable of adjustment to and from the forward or inner portion of the chair, so as to accommodate the said supporting means for effective engagement with window sills of varying width. This supporting means in the form illustrated in Figs. 1, 2 and 3, consists of a bottom bar 21, having upwardly extending side members 22. As shown in these views, the bottom of the frame B, rests upon the bar 21, and the sides of the frame are received between the side members or flanges 22, of the bar. In this way, the weight of the frame B and its occupant will serve to hold the support in adjusted position; but if desired, provision may be made for holding the bar 21 and its flanges 22 fixedly to the frame of the chair. In the structure herein shown the flanges 22 of the supporting member 21 are provided with vertically directed bearings 23, 23 wherein are held for vertical sliding movement the vertically directed upper parts or shanks of L-shaped legs or supporting members 24, 24, one of which is provided at each side of the chair, the lower ends of said legs being arranged to project beneath the frame and having their extremities provided with laterally directed extensions or feet 25, 25 which are integral with and project substantially at right angles from the vertically directed parts or shanks 50 of said legs or member 24, and have their undersides adapted to fit flush on the top surface of the window sill in such a way as to afford effective support for the outer part of the chair during use. The shanks of said legs 24 are capable of both rotatory and vertical sliding movement in the bearings 23, and said bearings have set screws 26 engageable with the shanks for holding the legs in adjusted position. By this construction of the parts it will be seen that when the screws 26 are loosened, the legs 24 may be adjusted to vary the extent to which their laterally directed feet or extensions 25 project beneath the frame, so as to accommodate different elevations of the window sill,

the shanks of said legs 24 playing freely endwise in the bearings 23 during such adjustment, and by rotating said legs their laterally directed feed or extensions 25 may be caused to project either inwardly or outwardly from their upper or shank portions, so as to accommodate the device to window sills of different widths without requiring adjustment of the legs horizontally upon the frame of the device, the shank portions of the legs or members 24 turning freely within the bearings 23 during such rotation of said legs or members.

In Fig. 6, I have illustrated a slight modification in the formation of the rear adjustable support for the seat frame, wherein a cross bar 27, is employed that slides beneath the frame, and said cross bar has upwardly extending members 28, at its ends of sufficient dimensions to constitute bearings, and each bearing has a vertical opening 30, to loosely receive the shank of a leg 24, and an opening 31, for the passage of a set screw to the shank of a leg. The flange extensions or bearing members 28 are extended up outside of the outer opposite surfaces of the side members 14 of the seat frame and are each provided with an inwardly extending guide member 29, which members are capable of sliding movement upon the upper faces of the side members 14, of the seat frame B, and said guide members 29, are provided with apertures 32, for the reception of set screws whereby to hold the support in adjusted position relatively to the seat frame B. As a further means for holding the said frame support in adjustment, screws 33, are passed up through the cross bar 27, being adapted to enter the seat. It may here be remarked that the seat may be secured to the frame B in any approved manner, and that the seat may be made of any suitable material, and that the seat frame may be provided with one or more handles 34.

As herein shown, the improved chair is provided with a back 35 of such shape and dimensions as to be adapted to conceal the occupant of the chair from passers-by. If desired, this back may be rigidly attached to the frame B or other part, or as herein illustrated may be hinged thereto so as to fold down over the seat portion of the chair when the device is not in use, so as to occupy as small a space as possible. To accomplish such pivotal or foldable connection of the back with the seat portion of the chair, said back 35 is provided at its opposite sides with integral forwardly directed portions 35^a, 35^a, which are pivoted at 36 upon alined lugs 37, produced at opposite sides of the frame B of said seat portion of the chair, the points of pivotal connection of said forwardly directed portions 35^a with the seat portion being closely adjacent to the upper

surface of the seat frame B, so that said back may be folded closely adjacent to the seat portion in order that the device may occupy comparatively small space when not required for use.

The forwardly directed portions 35^a, 35^a, at the opposite sides of the back 35 of the improved chair have forward edge surfaces 35^b, 35^b which are adapted, when the back 10 of the chair is in folded condition, to contact upon the top surface of the seat frame B along the opposite sides thereof in such a manner as to effectively retain the back 35 slightly elevated from the upper surface of 15 the seat portion of the chair, whereby a space or chamber is produced between the seat portion and back 35 when the chair is in folded condition, in which space or chamber cleaning rags or the like may be conveniently retained and carried about from 20 window to window.

The formation of the forwardly directed portions 35^a, at opposite sides of the chair back with the forward edge surfaces 35^b, 25 adapted to fit flush upon the top surface of the seat frame as above set forth, effectively closes the sides of the space or chamber between said back and seat portion of the chair when the device is compacted, and said 30 edge surfaces 35^b are rearwardly inclined from their lower parts toward the top of the chair back 35, so that when the back is folded down, closely adjacent to the seat portion of the chair, the upper edge of said 35 back 35, which then occupies a position adjacent to the forward edge of the seat portion, is caused to approach much closer to said seat portion than its lower edge portion, whereby it will be seen that the space 40 or chamber formed between the parts as above described, is substantially closed by such close approach of the top edge of the back toward the seat portion along the forward edge of the latter, thereby effectively 45 guarding against the falling of the cloths or other articles from said space or chamber when the device is carried from place to place. The formation and arrangement of the parts are also such that the lower edge of 50 the back 35, at points between the forwardly directed lateral portions 35^a, 35^a, is adapted to fit accurately upon the top surface of the frame member 13 when the back of the chair is raised, so that said forwardly 55 directed sides or lateral portions 35^a, 35^a being pivotally connected with the seat frame at points in advance of the point of contact of said lower edge of the back upon the seat frame, afford braces which operate effectively 60 for strengthening and bracing the chair back when the same is elevated during use of the improved chair.

It is obvious that the chair in its entirety 65 is very simple and that it may be made light and strong and can also be conveniently and

expeditiously placed in position on a window sill or removed therefrom.

What I claim as new and desire to secure by Letters Patent is—

1. A window cleaning chair having a 70 frame, supporting means comprising an L-shaped member having a vertically directed shank mounted for turning and endwise sliding movement upon the frame, and provided at its lower extremity with a laterally directed part integral with said vertically directed shank, and engageable with a window sill and adapted to be moved across the surface of such sill when the shank is turned upon the frame, and means for locking 75 said L-shaped member to the frame.

2. A window cleaning chair having a frame provided with bearings, L-shaped members each having a vertically directed shank mounted for turning and endwise 85 sliding movement in one of the bearings of the frame, and each provided at its lower extremity with a laterally directed part integral with said vertically directed shank and engageable with a window sill, and adapted to traverse the surface thereof during turning movement of said shank, and set screws for locking said members against movement in said bearings of the frame.

3. A window cleaning chair having a 95 frame provided with means for holding it to a window frame, and having a seat portion, and a back having forwardly directed rigid side portions at its opposite sides and pivotally connected with the frame adjacent 100 to the upper surface of its seat portion and in front of the rear edge thereof, said back when moved in one direction upon the pivotal connections of its side portions with the frame being adapted to stand vertically 105 above said frame with its lower edge engaged and supported upon the rear part of said frame and being adapted, when 110 reversely moved upon the pivotal connections of its side portions with said frame, to be folded down adjacent to the seat portion but spaced apart therefrom to produce a chamber between said back and the seat portion, the said forwardly directed side portions having edge surfaces adapted, when 115 the back is thus folded, to closely approach the seat portion and close the sides of said chamber.

4. A window cleaning chair having a frame provided with a seat portion, and a 120 back having forwardly directed side portions integrally produced at its opposite sides and pivotally connected with the frame adjacent to the upper surface of its seat portion and in front of the rear edge thereof, 125 said back when moved in one direction upon the pivotal connections of its side portions with the frame being adapted to stand vertically above said frame with its lower edge engaged and supported upon the rear part 130

of the frame, and being adapted, when re-
versely moved upon said pivotal connections,
to be folded down adjacent to the seat por-
tion, but spaced apart therefrom to produce
5 a chamber between said back and the seat
portion, the said forwardly directed side
portions of the back having edge surfaces
inclined from the pivotal connections of the
side portions toward the upper edge of the
10 back and adapted, when the back is folded,
to closely approach the seat portion and
close the sides of said chamber, the inclina-
tions of such edge surfaces being also adapt-

ed to permit the upper edge of the back,
when folded, to approach the seat portion 15
more closely than the lower edge of the back
and thereby close said chamber along the
forward edge of the seat portion.

In witness whereof I have hereunto
signed my name this 26th day of Septem- 20
ber 1908, in the presence of two subscribing
witnesses.

JOSÉ GONZALEZ BABIO.
